HAND PROTECTOR

Karl E. Jensen, Danville, Ill., assignor to Ervin
F. Kemp, Washington, D. C.

Application May 26, 1934, Serial No. 727,659

5 Claims. (Cl. 2-20)

The invention relates to hand protectors and more particularly to protectors of the type which are known generally as hand pads.

A general object of the invention is to provide 5 a protector of this type which is simple and economical to manufacture and is so constructed that the blanks from which the protector is formed may be cut with a minimum waste of material whereby the protector may be sold at 10 a low cost.

More specifically stated, an object of the invention is to provide a hand protector in the form of a covering of suitable protecting material shaped to fit over the palm side of the wearer's 15 hand and in which one portion of the palm covering is folded and secured upon itself to provide a thumb stall and which embodies an insert piece arranged to hold the side of the covering adjacent the thumb stall in rearwardly turned position to 20 provide protection for the index finger and wrist of the wearer.

In conjunction with the foregoing, another object of the invention is to provide a projection on said insert piece adapted to overlie and reinforce 25 the crotch of the thumb.

Other objects and advantages will become apparent in the following description and from the accompanying drawing, in which:

Figure 1 is a view of the rear side of a protector 30 embodying the features of the invention.

Fig. 2 is a front view of said protector.

Fig. 3 illustrates the shape of the large blank 35 from which the protector is formed.

Fig. 4 shows the shape of the insert blank.

While the invention is susceptible of various 40 modifications and alternative constructions, I have shown in the drawing and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

Referring to the drawing wherein a particular 45 embodiment of the invention is shown merely for illustrative purposes, 18 (Fig. 1) designates a hand protecting covering which is primarily formed from a blank of substantially regular form, as shown in Fig. 3, whereby the blank may be cut from a large sheet of material with a minimum of waste. Extending inwardly toward the center of the blank from one edge thereof is a slit 11 (Fig. 3) formed simply by making a cut in the blank without removing any of the material. This

cut divides the blank into what may be termed a hand section 12 and a thumb section 13.

With one side of the blank being selected as the front side (depending upon whether the finished protector is for the right or left hand), an 5 intermediate fold is made in the thumb section by turning the outer edge thereof, which parallels the cut, rearwardly into substantial registration with the marginal edge of the cut, the line of fold being approximately parallel to said cut as 10 indicated by the dotted line 14 in Fig. 3. The registering edges are secured together in any suitable manner, as by a line of metallic staples 15 (Fig. 1) to form the thumb stall 16.

The portion of the material on the other side of 15 the cut remains as a loose flap 17. When this flap is folded rearwardly, a relatively wide gap 20 between the edge of the cut on the flap and the rearwardly folded edge of the thumb stall section beyond the line of staples 15 is produced. This 25 gap is closed by an insert 18, the shape of which may be seen in Fig. 4. One edge 19 of the insert is shaped to abut and be secured to the marginal edge of the cut on the rearwardly folded flap 17, while another edge 20 of the insert is formed to 30 abut and be secured to the peripheral edge 28 (Fig. 3) of the thumb section beyond the line of staples 15. Any suitable means, such as metal staples 21, may be employed to secure the insert to the associated margins.

As may be seen in Fig. 1, the insert thus 35 produces a fold or curl 22 which is adapted to extend about the side and rear faces of the index finger and adjacent wrist portion of the wearer's hand whereby to afford a full measure of protection to these parts. Preferably a strap or the like 23 is secured to extend between the upper or finger portion of the curl 22 and an opposite side of the hand section, which strap is shorter than the flat distance between the parts connected thereby so as to definitely maintain the shape 40 of the fold 22 and to provide another fold 24 along the opposite side of the hand section for the protection of the outer or little finger side of the user's hand.

It is preferred that the insert 18 be provided 45 with a projection or tongue 25 of substantial length which is so located that, when the parts are assembled, the tongue will extend across and beyond the crotch of the thumb stall. Staples 26 or the like secure the tongue in this position, whereby to reinforce the crotch. Usually the front surfaces of the hand section and thumb stall have an overlying reinforcing sheet 27 se-

cured thereto as by staples 28. Where this reinforcement is used, a notch 29 is formed therein to receive the tongue 25, thus avoiding an undesirable accumulation of material at this point.

5 It will be evident from the foregoing that a novel protecting means has been provided wherein the hand covering, due to its regular shape, may be fashioned without undue waste of material, while the insert 18 and strap 23 may be fashioned from 10 pieces of scrap material. The comparatively few parts which comprise the completed article may be easily and speedily fastened together, and these lines of fastening are, for the most part, disposed on the rear side of the protector where 15 they are not subject to wear or excessive strain. The article, therefore, has ample strength to withstand such rough usage as would be encountered in industrial plants, is fashioned to afford ample protection to the wearer, and may 20 be manufactured and sold at a relatively low cost.

I claim as my invention:

1. A hand protector comprising, in combination, a sheet of protecting material fashioned to 25 provide a blank having a cut extending inwardly from one edge to separate the blank into hand and thumb sections, said thumb section being bent upon itself intermediate said cut and an edge of the blank paralleling said cut to bring said edge 30 and the thumb section edge of the cut into registration, means for securing the registering edges together to form a thumb stall, a strap secured adjacent to the corner of the hand section formed by said cut and to an opposite edge portion of the hand section to provide folds adapted to extend 35 around the wearer's index and little fingers, and an auxiliary piece secured to the cut edge of the hand section and to the marginal edge of the thumb section beyond said registering edges to 40 close the gap therebetween, said piece having a tongue extending across the crotch between the thumb stall and said fold and secured near the palm side.

2. A hand protector comprising, in combination, 45 a sheet of protecting material fashioned to

provide a blank having a cut extending inwardly of the sheet from one edge to separate the blank into hand and thumb sections, means for securing the outside edge of said thumb section to the adjacent side edge of said cut to form a thumb stall, means for holding the opposite side edge of said cut folded for the protection of the index finger, and an insert secured to traverse the gap between said opposite side edge of the cut and the outside edge of the thumb section beyond the 10 thumb stall.

3. In a hand pad, the combination of a protecting covering having a slit therein, one part of said covering being folded and secured to one margin along said slit to form a thumb stall, 15 and an insert secured to said folded part and to the other margin along said slit and having a projecting piece secured in overlying relation to the thumb stall crotch.

4. In a hand pad, the combination of a protecting covering having a slit therein, one part of said covering being folded and secured to one margin along said slit to form a thumb stall, and an insert secured to said folded part and to the other margin along said slit to form a permanent 25 curl along one side of the covering adjacent to said thumb stall for the protection of the index finger and adjoining wrist portions of the wearer's hand.

5. In a hand protector, the combination of a 30 protecting covering comprising a blank having a cut therein extending a limited distance inwardly from one edge dividing the blank into hand and thumb sections, said thumb section being folded with the outer edge secured adjacent the margin along said slit to form an enclosed stall adapted for completely encircling and 35 substantially protecting the wearer's thumb, and an insert secured to said folded part beyond the edge and margin juncture and to the hand section margin along said slit to form a permanent curl along the side of the hand section adjacent to said thumb stall for the protection of the index finger and the adjoining part of the back of the wearer's hand.

KARL E. JENSEN.
